UNITED STATES PATENT OFFICE.

CARL J. ULMANN, OF NEW YORK, N. Y.

RECEPTACLE FOR THREAD, CORD, SILK, AND THE LIKE.

1,029,094.

Specification of Letters Patent. Patented June 11, 1912.

Application filed February 8, 1911. Serial No. 607,422.

To all whom it may concern:

Be it known that I, CARL J. ULMANN, a citizen of the United States, and resident of the borough of Manhattan, city, county, and State of New York, have invented certain new and useful Improvements in Receptacles for Thread, Cord, Silk, and the Like, of which the following is a specification.

My invention relates to receptacles for thread, cord, silk, twine and the like and more particularly for balls of sewing or crocheting silk and has for its object to provide a receptacle of this kind which will protect its contents and at the same time 15 provide an attractive sealed package for the display and sale of the article.

A further object of my improvement is to so construct the receptacle or package that it may be used as a container from which 20 the silk or other material may be drawn as needed for use, an arrangement which makes it unnecessary to remove the entire ball of silk or other material each time a length thereof is wanted. The contents of 25 the receptacle are thus guarded against entanglement and also against soiling by promiscuous handling or otherwise either while displayed for sale or during use.

Other objects of my invention will appear from the description hereinafter and 30 the features of novelty will be pointed out in the appended claim.

Reference is to be had to the accompanying drawings in which—

35 Figure 1 is a central sectional elevation of my improved receptacle or package; Fig. 2 is a plan view thereof and Fig. 3 is an inverted plan view.

In the particular form illustrated the receptacle 40 comprises two sections *a* and *b* in one of which an inner wall *c* is secured in any convenient manner as by gluing. The inner wall *c* projects beyond the section in which it is secured and forms a flange upon 45 which the other section may be placed as clearly shown in Fig. 1. With this construction the outer surfaces of the two sections *a* and *b* are flush, the said sections preferably being fastened together against 50 relative movement by means of a sealing strip *d* which is pasted or otherwise secured to said sections so that it extends over the line of contact thereof. This sealing strip *d* may be in the nature of a label upon 55 which suitable advertising matter or identifying marks may be produced. If de-

sired one box section may be made to slidably fit over the other section instead of as shown and so far described. In either case the one section *a* is provided in its wall *e* 30 with a comparatively large opening preferably covered by a transparent plate or closure *f* of glass or the like through which the contents *g* may be viewed without opening the package and which protects the contents 35 against soiling and injury. The other section *b* is provided in its wall *h* with a small central aperture *i* preferably reinforced by a smooth eyelet *j* through which the silk cord or similar article may be drawn for 40 use, so that it is unnecessary to open the package to take out the contents each time a length of silk, cord or other article is desired. In the original package the one end of said silk, etc., may extend through the 45 said aperture *i* and be secured beneath a wafer or seal *k* which is glued to the outer face of the wall *h*. When it is desired to begin using the silk or other article contained in the receptacle this seal *k* is broken 50 thus leaving the end and the remainder of the contents free to be drawn through said aperture *i* as required. The eyelet *j* prevents the silk etc. from contacting with the rough edges of the aperture *i* and being 55 smooth reduces friction and protects the silk, etc., against tearing or other injury as it is withdrawn for use.

My improved receptacle thus provides a sealed package for thread, silk, cord and 60 the like which presents an attractive appearance and which protects its contents against injury, dust, and soiling by promiscuous handling. The said receptacle 65 also presents the contents to view through the transparent plate *f* and serves as a container for said goods until the same is completely used, so that it is unnecessary to at 70 any time or for any purpose, unseal the package either to view its contents or to remove the same for use. Furthermore by sealing the package it is impossible to substitute other and inferior goods or to in 75 any way again use the receptacle without detection so that the purchaser is guaranteed against unscrupulous dealers.

Various changes in the specific form shown and described may be made within the scope of the claim without departing 80 from the spirit of my invention.

I claim:

A receptacle of the kind described com-

prising two axially alining tubular sections in butt joint engagement with each other, a relatively narrow flange extending inwardly at the free end of one of said sections to form a relatively large opening for exposing the contents to view, a transparent closure secured to the inner surface of said flange to cover the opening formed thereby, a wall substantially closing the 10 free end of the other section and provided with an eyelet through which the contents may be withdrawn, said eyelet being diametrically opposite the said transparent closure, an exterior sealing strip extending

about said sections so as to bridge the joint 15 thereof and maintain said sections in engagement with each other, and an inner wall secured to one of said sections and extending beyond the same into frictional engagement with the other section. 20

In testimony whereof, I have hereunto set my hand and seal in the presence of two subscribing witnesses.

CARL J. ULMANN.

Witnesses:

JOHN A. KEHLENBECK,
M. H. LOCKWOOD.
